(57) **CLAIM**

The ornamental design for a modular furniture hanger, as shown and described.

DESCRIPTION

FIG. 1 is a perspective view of a modular furniture hanger showing my new design in use;

FIG. 2 is a perspective view showing my new design in use;

FIG. 3 is an enlarged side view thereof;

FIG. 4 is a front view thereof;

FIG. 5 is a rear view thereof;

FIG. 6 is a top view thereof; and,

FIG. 7 is a bottom view thereof.

The modular furniture panel, purse and umbrella shown in broken lines in FIG. 1 and the modular furniture panel and cables shown in broken lines in FIG. 2 are for illustrative purposes only and form no part of the claimed design.
